Edmund Tolbert

Attorney

UNITED STATES PATENT OFFICE.

HENRY P. FULLER, OF RICHMOND, VIRGINIA.

GARBAGE RECEPTACLE AND INCINERATOR.

Application filed August 27, 1921. Serial No. 495,892.

To all whom it may concern:

Be it known that HENRY P. FULLER, a citizen of the United States of America, residing at Richmond, in the county of Henrico and State of Virginia, has invented new and useful Improvements in Garbage Receptacles and Incinerators, of which the following is a specification.

The object of the invention is to provide a simple, comparatively inexpensive and efficient garbage can or receptacle adapted for the reception of garbage and like refuse as it accumulates and provided with means whereby the contents of the can or receptacle may be incinerated at intervals to provide for the removal only of the ashes or dried residue when it is desired to empty the same; and furthermore to provide in this connection means whereby flies approaching the receptacle may be trapped and destroyed in the course of incineration of the contents of the receptacle; and with these objects in view the invention consists in a construction and combination of parts of which a preferred embodiment is shown in the accompanying drawings, wherein:

Figure 1 is a side view, and

Figure 2 is a vertical sectional view of a garbage receptacle embodying the invention.

Figure 3 is a plan view of the same.

The receptacle casing 10 is preferably of cylindrical form with a spherically rounded bottom 11 having a suitable filler 12 of concrete or the like to form a weight by which the receptacle while capable of rocking movement is prevented from overturning and is normally held in an upright position, and the interior of the receptacle is divided by suitable partitions to form a garbage compartment 13 and a combustion chamber or fire box 14 directly beneath the garbage compartment and occupying the lower portion of the casing with an upright smoke flue 15 leading from the combustion chamber with a vent or outlet 16 at the upper end thereof in communication with the upper portion of the garbage compartment.

Removably fitted upon the top of the cylindrical wall of the casing as by means of a slip joint is a cover 17 provided with laterally extending eyes 18 mounted upon parallel guides 19 constituting elements of a bail

or handle 20 which is pivoted as at 21 to the wall of the casing to the end that while the cover may be raised by sliding the eyes on 55 the guide elements 19 to expose the upper end of the casing and the garbage compartment therein for the reception of garbage, the complete detachment of the lid or cover is prevented. To expose the entire top of 60 the receptacle the lid or cover after being raised to the limit of its movement on the guides 19 may be swung laterally by reason of the pivoting of the bail or handle.

Within the lid or cover which is of domed 65 form as shown with a central opening 22 designed to afford an outlet for smoke and other products of combustion, is arranged a cage 23 having a bottom perforated wall 24 and having circuitous inlet passages 25 70 through which flies lighting upon the gauze wire or screen diaphragm 26 covering the neck or opening 22 may find access to the cage, without, however, being permitted by reason of the screen 24 from gaining access 75 to the garbage compartment.

In practice as will be obvious the lid or cover may be raised from time to time to deposit garbage or waste materials in the receptacle 13 and at stated or preferred intervals paper or like combustible material may be introduced into the combustion chamber or fire box 14 through an opening fitted with a hinged door 27 and ignited for the purpose of incinerating the contents of the garbage compartment and obviously destroying flies which have accumulated in the cage 23, to the end that the interior of the receptacle may be cleansed from time to time by the discharge therefrom of the ash and dried 90 residue of the incinerating processes.

Having described the invention what is claimed as new and useful is:—

A garbage receptacle comprising a casing having an interiorly located garbage receiving compartment, the wall of which is spaced from the bottom of the casing, thereby providing a fire space and smoke flue space within the casing, a screen located in the upper portion of the casing and bridging 95 the smoke flue, a cover for the casing, a perforated plate carried by the cover and adapted to extend over the end of the casing and the ends of the garbage compartment and

smoke flue therein, a cage located under the cover and mounted upon said plate, the cover being provided at its center with an opening, a screen disposed over the opening, and tortuous tubes passing through the screen and the top of the cage and having their lower ends disposed above the plate,

said tubes adapted to serve as means for permitting insects to enter the cage and the products of combustion and evaporation from the can to pass from under the cover. 10

In testimony whereof he affixes his signature.

HENRY P. FULLER.
